UNITED STATES PATENT OFFICE.

EGON HANDL, OF AMSTERDAM, NETHERLANDS.

MEANS FOR CONNECTING FERRO OR REINFORCED CONCRETE PILES TO WOODEN PILES.

Application filed July 14, 1923. Serial No. 651,644.

To all whom it may concern:

Be it known that I, EGON HANDL, a subject of the Kingdom of the Netherlands, residing at Amsterdam, Netherlands, have **6** invented certain new and useful Improvements in or Relating to Means for Connecting Ferro or Reinforced Concrete Piles to Wooden Piles (for which I have filed an application in the Netherlands September **10** 8, 1920), of which the following is a specification.

Various means have been proposed for fixing reinforced concrete or ferro-concrete piles on top of wooden ones. It has, for **15** instance, been suggested to make the upper end of the wooden pile smaller in diameter and to provide the lower end of the ferro-concrete pile with a socket portion which fits over the reduced upper end portion of **20** the wooden pile, the bottom of the socket resting upon the top face of the reduced upper end of the pile and the lower edge portion of the socket resting upon a shoulder formed at the lower end of the reduced **25** top portion of the wooden pile. Such connections are incapable of taking up horizontal forces, as the tubular or socket portion of the ferro-concrete pile usually breaks at the point corresponding to the **30** top end of the reduced upper portion of the wooden pile upon the occurrence of a horizontally acting pull.

Other known modes of connecting wooden and concrete piles are even less suitable **35** for taking up horizontal forces.

It is the object of the present invention to provide improved means of connection of the kind referred to above which are **40** suitable for taking up or transmitting considerable horizontal forces without any danger of the tubular extension or socket of the ferro-concrete pile breaking at the point of connection.

The invention consists mainly in enclosing **45** the bearing surface between the upper reduced end of the wooden pile and the ferro-concrete pile by a tightly fitting sleeve made of iron or steel. This sleeve may, if desired, be provided at its lower end with **50** a horizontal flange resting upon the shoulder formed at the lower end of the reduced upper portion of the wooden pile. This connecting sleeve is entirely embedded in con-

crete and is therefore sealed against the action of the air so that it cannot rust and **55** cannot cause the ferro-concrete to be attacked by rust.

By these means an extremely rigid and **60** strong connection between the wooden pile and the ferro-concrete extension pile is attained which is absolutely safe against breaking or cracking upon the occurrence of laterally acting forces. This connection has also the advantage of protecting the upper end of the wooden pile against **65** cracking.

The invention is illustrated by way of example in the accompanying drawing; Fig. 1 showing a vertical section through the upper end of the wooden pile and the **70** connecting sleeve, Fig. 2 is a section through a wooden pile and a concrete pile or extension piece secured to the top of the wooden pile, and Fig. 3 is a vertical section similar to Fig. 1 but shows a modified **75** connecting sleeve.

In the drawing 3 represents the iron or steel sleeve which fits tight upon the end **80** 2 of the wooden pile 1, which has been previously reduced in diameter or made of smaller size. This sleeve is embedded in the ferro-concrete pile 4 so as to enclose a core portion 5 of concrete which when the two piles are connected rests upon the top **85** of the end portion 2. It will therefore be seen that the bearing surface between the parts 2 and 5 is enclosed by the connecting sleeve 3. The connecting sleeve may, if required, be provided with a horizontal **90** flange at its lower end resting upon the shoulder 6 of the wooden pile 1.

I claim as my invention:

1. A pile comprising a wooden base provided with a reduced cylindrical portion; a metal sleeve on said reduced portion extending beyond the end of said base; and a concrete upper portion on said base having an internal, axial core which extends into and fills the projecting upper portion of **95** said sleeve and entirely surrounds said sleeve.

2. A pile comprising a wooden base provided with a reduced portion and a shoulder at the foot of said portion; a metal sleeve on said reduced portion extending beyond the end of said base and having a **100** 105

flange adapted to rest on said shoulder; and a concrete upper portion on said base having an internal, axial core which extends into and fills the projecting upper portion of said sleeve and entirely surrounds said sleeve, said concrete portion also resting on said flange of the sleeve.

In testimony whereof I affix my signature.

EGON HANDL.
